United States Patent Office.

CHARLES C. PLAISTED, OF HARTFORD, CONNECTICUT.

Letters Patent No. 73,925, dated January 28, 1868.

IMPROVED WINDOW-SCREEN.

The Schedule referred to in these Letters Patent and making part of the same.

TO ALL WHOM IT MAY CONCERN:

Be it known that I, CHARLES C. PLAISTED, of Hartford, in the county of Hartford, and State of Connecticut, have invented a new and improved Self-Adjusting Window-Screen; and I do hereby declare that the following is a full, clear, and exact description thereof, reference being had to the accompanying drawings, and to the letters of reference marked thereon.

Figure 1 shows a front view of a window having the improved self-adjusting screen attached to both top and bottom sashes.

Figure 2 shows a section of the window, with an end view of the screens and accompanying parts.

My invention consists in attaching the screen to the window-frame and sash in such a manner that when the sash is opened the screen covers the opening, however much or little the sash may be moved, by unrolling from a roller, which may be attached either to the sash or window-frame, as shown in the drawings in the two sashes. When the sash is closed the roller takes up the screen, so that it is constantly kept tight and in place.

My invention also consists in the manner in which the screen is secured at the sides, either by small pins or projections, on which it is hooked as it is unrolled, or by a clamp at the side, as shown in the drawings, or by both these devices conjointly.

To enable others skilled in the art to make and use my invention, the following is a description of its construction and operation:

The screen S or S' is made of mosquito-net, or any other suitable material, and winds on the roller R or R', which is fitted with springs at s s, or any other common mechanical contrivance, which will exert a continual tension upon the screen, and admit of sufficient motion in unrolling to allow the screen to be drawn off in opening the sash, and rewind it when closed. In the lower sash, shown in the drawings, the roller R is secured to the window-frame F, and the upper edge of the screen is secured to a bar, B, which hooks on to, or is otherwise secured to, the sash A, so that it can be readily detached when it is not desired to have the opening of the window covered by the screen. When the screen is unrolled, the edges pass into the grooves g g, and can be secured in any position of the sash by the clamp-bar E, which is operated by the eccentric clamp C, or any other suitable device. In the upper sash, shown in the drawings, the roller R' is secured to the sash A', and the upper edge of the screen is attached to the bar B', which is so attached to the window-frame, by any common mechanical contrivance, that it can readily be detached, and move up and down with the sash when the screen is not desired to cover the opening of the window. When the sash is opened, the screen unrolls, as before described, but in this case, in place of having the edges secured in a groove, g, as in the lower sash, another method is shown, viz, the edges are caught upon pins or hooks b on the bars D, the edges being guided and pressed against D by the projection a upon the bracket which carries the roller R'.

The operation of my invention is as follows: When the sash is opened, the screen is unrolled from the roller by the act of opening the window in the ordinary manner and covers the opening, the edges being secured as before described. When the sash is closed, the action of the roller winds up the screen, keeping it at a proper tension at all the different heights the sash may be placed. Either of the two methods of mounting the screen herein described may be used both for the top and bottom sashes.

What I claim as my invention, and desire to secure by Letters Patent, is—

1. The combination of the screen and pins b, in the manner and for the purpose herein set forth.
2. The combination of the screen and clamp or clamp-bar E, in the manner and for the purpose herein set forth.

CHARLES C. PLAISTED.
